UNITED STATES PATENT OFFICE.

PHILIP A. BOWEN, OF LYNN, MASSACHUSETTS, ASSIGNOR TO LILLIAN A. LITTLE, OF LYNN, MASSACHUSETTS.

SHOE TREE OR FORM.

986,680.

Specification of Letters Patent.

Patented Mar. 14, 1911.

Application filed July 21, 1910. Serial No. 572,961.

To all whom it may concern:

Be it known that I, PHILIP A. BOWEN, a citizen of the United States, and resident of Lynn, county of Essex, State of Massachusetts, have invented an Improvement in Shoe Trees or Forms, of which the following description, in connection with the accompanying drawing, is a specification, like characters on the drawing representing like parts.

This invention has for its object the production of a novel and efficient shoe-tree or form primarily designed for use in keeping a shoe in shape when not in use.

In the present embodiment of my invention the fore part and heel part of the tree are pivotally connected by longitudinally extensible means whereby the heel part may be swung or tipped up relatively to the fore part, to provide for ready insertion in the shoe and removal therefrom, and I have provided a controlling device which co-operates with such connecting means to shorten the same when the heel part is tipped and to lengthen such means when the tree is positioned in the shoe. This extensibility of the connecting means is of great assistance in manipulating the tree, as the same can be inserted in and removed from the shoe with ease, and when the tree is positioned in the shoe the separation of the fore and heel parts moves them into place to keep the shoe in proper shape. To accommodate a given shoe-tree to shoes of different lengths, within reasonable limits, I have provided self-acting means to accommodate the effective length of the tree to the length of the shoe, and I have also made a similar provision for governing the effective width of the fore part of the tree. Thus without any adjustment a tree of a given size automatically accommodates itself to a number of different sized shoes.

The various novel features of my invention will be fully described in the subjoined specification and particularly pointed out in the following claims.

Figure 1 is a partial longitudinal section of a shoe-tree or form embodying my invention, on the line 1—1, Fig. 2, but with the connecting means shown partly in section and partly in elevation, the tree being extended and operatively positioned in a shoe;

Fig. 2 is a bottom view of the shoe-tree shown in Fig. 1; Fig. 3 is a detail of the fore and heel parts, looking toward the toe of the tree, when the heel part is tipped up with relation to the fore part; Fig. 4 is a view similar to Fig. 1, but showing in full lines the fore and heel parts brought together by the shortening of the connecting means between such parts, and the heel part is shown by dotted lines in tipped position for the insertion or removal of the tree; Fig. 5 is a longitudinal section and part elevation of a modified form of the tree, wherein the fore part is non-expansible; Fig. 6 is an enlarged transverse sectional detail, on the line 6—6, Fig. 4, looking toward the right, to illustrate more clearly a part of the connecting means, to be referred to; Fig. 7 is a perspective view, broken out, of the part of the connecting means which is fixedly secured in the heel part of the tree; Fig. 8 is a similar view of the member of the connecting means which is pivotally attached to the divided fore part shown in Fig. 4; Figs. 9 and 10 are perspective details of the metallic seats which are secured in the fore parts of the tree, as illustrated in Figs. 4 and 5 respectively.

Inasmuch as the connecting means between the fore and heel parts is substantially the same in both the structures illustrated I will describe the same in detail with relation particularly to Figs. 1, 3, 4 and 6, and make such particular reference to Fig. 5 as may be necessary for a clear understanding thereof. Herein the heel part is indicated at H, and the fore part at F, the heel part being of the usual character employed in a shoe-tree or form of this general description, and herein said heel part H is provided with a longitudinal recess 1 extended from its front end rearward and open at its top, the recess being shown as rectangular in cross section. The bottom of the recess has a longitudinal groove or depression 2, for a purpose to be described, and the wood of the heel part is socketed at 3 at the rear end of the recess. In this socket I seat a tubular member 4, preferably made of sheet metal and of rectangular cross-section, having its longitudinal upper edges inturned to form overhanging, opposed flanges 5, a tongue 6 downturned from the front end of

said member being fixedly attached by a suitable fastening 7 to the front end of the heel part, the rear end of the bottom of said member 4 being extended at 8 to enter the 5 socket 3. Thus said member is securely held in place in the heel part, and as shown in Figs. 1, 4 and 6 the bottom of the member is longitudinally slotted at 9 above the groove 2. In such fixedly held member I 10 mount a longitudinally slidable or telescoping member 10 of corresponding cross-section and snugly fitting therein, the member 10 being made as a rectangular, metallic tube, and provided with a longitudinal slot 15 11 in its top at its rear, open end. At its front end the member 10 is pivotally attached by a transverse pin 12 to the fore part of the tree.

Having reference now particularly to Fig. 20 5 the fore part F is solid, or non-expansible, and at its rear end it has a longitudinal recess 13 to receive an open metallic seat 14, Fig. 10, its bottom being downturned at 15 against the end of the fore part and secured 25 thereto by a suitable fastening 16. The opposite end of the seat bottom is prolonged at 17 to enter a slot 18, so that the seat is maintained securely in place, the pin 12 being mounted in the upturned walls of the 30 seat.

It will now be apparent that the member 10 is pivotally attached to the fore part of the tree and is in longitudinally slidable engagement with the heel part, through its 35 telescopic coöperation with the member 4, so that a connection is effected between the fore and heel parts, enabling the latter to be tipped or swung with relation to the former, and by the extensibility of such connection 40 the fore and heel parts can be moved toward and from each other.

An abutment 19 is formed in the member 10 by slitting its bottom and turning up the tongue so formed, said abutment being just 45 behind the pivot 12 and sustaining one end of a coiled spring 20, shown only in Figs. 1, 3 and 4. The other end of the spring abuts against a plunger 21 slidable in the connecting member 10 and longitudinally 50 slotted at 22, Fig. 1, and dotted lines Fig. 4, to receive one end of a link 23, pivotally connected with the plunger at 24, and having a downturned lug or hook 25 which passes through a slot 26 in the bottom of the member 10, and through the slot 9 in member 4, into the groove 2.

Referring to Fig. 8 the only difference in the member 10 when used with a divided fore part over its construction when used 60 with a solid fore part, as in Fig. 5, is that in the first case the member 10 is extended at 27, Fig. 8, beyond the pivot point and provided with short slots 28 in its top and bottom, the sides having opposite openings 29 65 for a purpose to be described. By compar-

ing Fig. 8 with Fig. 5 it will be seen that the other portion of the member 10 is the same in all of its details.

The free end of the link 23 is pivotally connected at 30 with a controlling device 70 or arm 31 fulcrumed on a cross pin 32 held in the sides of the fixed member 4 close to the rear end thereof, said arm being prolonged at 33 beyond the pivot 30 and apertured to form a finger piece or handle. As 75 shown in Figs. 1, 4 and 5, the link 23 and connected arm 31 form a species of toggle, which when set or straightened as in Fig. 1 holds the member 10 in extended position and fixedly positions the plunger 21, for the 80 joint 30 is at such time just below a line connecting the pins 24 and 32.

The member 10 cannot be pulled out of the fixed member 4 because the hook 25 projects through the slot 26 at all times, and the 85 engagement of such hook with either end of the slot limits relative longitudinal movement of the members 10 and 4.

When the controlling device or arm is 90 swung down by its handle 33 into operative position, Fig. 1, the fore and heel parts are moved away from each other, the members 10 and 4 sliding or telescoping one with relation to the other, but the heel and fore parts can be yieldingly pressed toward each 95 other, the spring 20 being compressed between the abutment 19 and the fixedly positioned plunger. This permits a considerable variation in the effective length of the tree, so that a tree of a given size can fit 100 shoes of a number of different sizes.

To place the tree in a shoe the controlling device is first swung up into the position shown in Figs. 4 and 5, the hooked end of the link 23 thereby drawing inward the 105 plunger and the member 10, the latter sliding into the fixed member 4 and drawing the heel and fore parts together. Now the heel part is swung or tipped up on the pivot 12, as indicated by dotted lines Fig. 4, and the tree is inserted in the shoe. After the fore part properly enters the toe portion of the shoe the heel part is swung down into operative position into the heel of the shoe, Fig. 1, and the controlling device 31 is swung down to operative position, as shown in Fig. 1, extending the connecting means between the heel and fore parts of the tree and pressing them firmly into the corresponding portions of the shoe. As soon as the parts of 110 the tree seat properly in the shoe the continued downward swing of the handle 33 to set the toggle 23, 31 acts through the plunger 21 to compress spring 20 more or less, according to the length of the shoe, the 115 expanding action of the spring thus serving to retain the tree securely in place. The spring thus constitutes a self-acting means to accommodate the effective length of the tree to the length of the shoe in which it is 120

125

130

placed. When the tree is to be removed the operation described is performed in reverse order, first to unlock the toggle and shorten or contract the connecting means between the fore and heel parts, and then the latter is swung up to permit ready withdrawal of the tree.

Whether the fore part be laterally expansible, as in Figs. 1, 2 and 4, as will be explained, or whether it be solid, as in Fig. 5, the foregoing description and explanation of construction and operation apply. When, however, the fore part is divided I utilize the swinging movement of the connecting means to contract the fore part when the tree is inserted in or is to be removed from the shoe, and to spread or expand laterally said fore part when the tree is straightened out in the shoe.

While the fore part is indicated as a whole at F the two portions thereof in Figs. 2 and 3 will be distinguished one from the other by reference letters f , f^* , the former portion being the larger of the two, a vertical, longitudinal cut from the toe rearward separating such portions. Transverse and parallel guide pins 34 fixedly held in the portion f^* slide in sockets 35 in the portion f , and communicating recesses 36, 36^* are made in the bottoms of the portions f , f^* , Fig. 2, to receive short and like links 37, pivotally connected at 38, one link having its outer end fulcrumed at 39 in the recess 36 while the other link is similarly fulcrumed at 40 in the recess 36^* . The pivotal connection 38 between the links is connected also with the lower, front end of an inclined tubular member 41 which is longitudinally slidable in a recess 42 provided therefor in the inner wall of the portion f , the top of the recess having a longitudinal, grooved portion 43. Said member 41 contains a coiled spring 44 and a slidable plunger 45, the spring interposed between the plunger and the lower end of the tubular member, a link 46 being jointed to said plunger by a pin 47 and having an upturned hooked end 48 to enter the groove 43 after it passes through a slot 49 in the member 41. The upper end of the link 46 is extended into the slots 28 in the extension 27 of the connecting member 10, Fig. 8, and pivotally connected therewith by a cross-pin 50 held in the openings 29 in said extension. Now when the controlling arm 31 and its handle 33 are in operative position, Fig. 1, the member 10 is held in outwardly extended position, and the spring 44 acting against the then fixed plunger 45 presses the tubular member 41 downward and forward, to maintain the links 37, 37 in alinement and thereby laterally expand the divided fore part of the tree, see Fig. 2. When the heel part H is swung up into dotted line position Fig. 4, about the pin 12 as a fulcrum, the link 46 is drawn downward and rearward, as indi-

cated, its hooked end 48 pulling with it the member 41 to thereby swing the cross links 37 rearward and pull together the two portions f , f^* , as in Fig. 3. The contracted fore part is then inserted in the shoe, and when the heel part is swung down to the position shown in Figs. 1 and 4 the link 46 pushes forward the plunger 45, compressing the spring 44, the expansive action of the latter in turn acting to move the tubular member 41 downward and forward to aline the links 37 and thus spread or expand laterally the fore part. If the shoe be a narrow one the fore part will be expanded to snugly fit it and then the spring will be further compressed as the heel part is fully positioned. Hence with a divided fore part the construction is such that such fore part accommodates itself automatically (so far as concerns its effective width,) to the width of the shoe, said fore part being contracted by the upward swing of the heel part preparatory to withdrawing the tree from the shoe.

Owing to the two-piece construction of the divided fore part I have to modify the metallic seat in which the connecting member 10 is pivoted, as will be seen by a comparison of Figs. 9 and 10. In Fig. 9 the seat has upturned, oppositely apertured sides 51, 52 between which the front end of the member 10 is pivoted by the pin 12, and in this form said pin can also be made as a screw to enter the wood of the portion f , and assist the screw 53, Fig. 3, in securing the seat in place, the latter passing through a depending ear 54 on the seat. The bottom 55 of the seat is cut away between the sides to permit the swinging movement of the connecting member 10, as will be apparent.

Various changes or modifications in details of construction and arrangement may be made by those skilled in the art without departing from the spirit and scope of my invention as set forth in the claims annexed hereto.

Having fully described my invention, what I claim as new and desire to secure by Letters Patent is:—

1. A shoe-tree or form comprising a fore part and a heel part, a connection therebetween comprising a tubular longitudinal member fixedly secured at its ends to one of said parts, and a coöperating, telescopic member pivotally connected with the other of said parts and slidable within said tubular member, an expansion spring and a plunger within the pivoted member of the connection, a controlling arm fulcrumed on the fixedly secured member of the connection, and a link pivotally connecting said arm with the plunger and separately connecting the arm and the pivoted member of the connection, swinging movement of the arm acting through the link to move telescopically the members of the connection and thereby

draw toward each other or separate the fore and heel parts, the spring permitting the fore and heel parts to adapt themselves to the length of the shoe when the arm is swung 5 to separate said parts.

2. A shoe-tree or form comprising a fore part, and a heel part, an open seat fixedly attached to one of said parts, and a tubular, longitudinal member fixedly attached to the 10 other part, a connecting member pivotally attached to the seat and longitudinally slidable in said tubular member, said connecting and tubular members being longitudinally slotted, a controlling arm fulcrumed on the 15 tubular member to swing in said slots, a link operatively connecting said arm and the connecting member to slide it in or out of the tubular member and thereby draw toward each other or to separate the fore and 20 heel parts, and a yieldingly-controlled plunger slidable in the connecting member and pivotally connected with the link to permit the fore and heel parts to adapt themselves to the length of the shoe when said arm is 25 positioned to maintain said parts separated, said link having a slidable engagement with the connecting member.

3. A shoe-tree or form comprising a longitudinally divided fore part and a heel part, a connection pivotally attached to one and 30 in longitudinal sliding engagement with the other of said parts, means co-operating with said connection to move said parts positively toward and from each other, de- 35 vices controlled by said connection to expand or contract said fore part according to the position of the connection, and self-acting means yieldingly separating said fore and heel parts while permitting movement 40 thereof toward each other irrespective of said positively acting means.

4. A shoe-tree or form comprising a heel part and a longitudinally-divided fore part, a connection pivotally attached to the latter and in longitudinal slidable engagement 45 with the heel part, means to laterally contract said fore part when said connection is swung upward on its pivot and to expand the fore part when the connection is in operative position, and a device to co-operate 50 with said connection and move the heel and fore parts toward and from each other.

5. A shoe-tree or form comprising a heel part and a longitudinally-divided fore part, a connection pivotally attached to the latter 55 and in longitudinal slidable engagement with the heel part, and means governed by swinging movement of the connection out of and into operative position to contract and expand, respectively, the divided fore 60 part of the tree.

6. A shoe-tree or form comprising a heel part and a longitudinally-divided fore part, a connection pivotally attached to one and having a longitudinal sliding engagement 65 with the other of said parts, a device co-operating with said connection to move the heel and fore parts toward and from each other, means governed by swinging movement of the connection out of and into operative position to contract and expand, respectively, the divided fore part, and self- 70 acting yielding means to accommodate the effective width of the fore part to the width of the shoe when positioned therein.

In testimony whereof, I have signed my name to this specification, in the presence of two subscribing witnesses.

PHILIP A. BOWEN.
